Primary Examiner—Terry A Wallace

[57] **CLAIM**

The ornamental design for a snap-together linearly connectable canister, as shown and described.

DESCRIPTION

FIG. 1 is a reduced scale perspective view of the invention, shown in combination with two other units of the invention in phantom lines;

FIG. 2 is a perspective view of the invention;

FIG. 3 is a side elevational view; all sides are identical;

FIG. 4 is a top plan view;

FIG. 5 is a bottom plan view;

FIG. 6 is an enlarged and fragmented side sectional view taken along line 6—6 in FIG. 4, showing the surface contour details not clearly revealed in the other views.
